UNITED STATES PATENT OFFICE

GEORGE A. MATTHEWS AND JOSEPH J. SHOEMAKER, OF DETROIT, MICHIGAN

SWITCH

Application filed January 10, 1930. Serial No. 419,789.

The present invention relates to switches and more particularly to interlocking disconnecting switches.

One of the objects of the invention is to provide a gang switch having a number of switch arms fixedly mounted upon a rotating shaft, the shaft in its rotary movement carrying all the arms from one position to another in a rapid and positive manner.

10 Another object is to provide a casing for a movable gang switch, the casing being divided by suitable insulating partitions, into a number of sections or cells, so that the contacts are completely shielded from one another, whereby short-circuiting due to flash-over between contacts will be prevented.

A further object of the invention is to provide a casing for movable switch arms, the casing being provided with a slotted baffle 20 plate adapted to be traversed by arms in their movement, the slots being provided with shutters which are automatically movable to close and open said slots as the arms pass through them from one section of said casing 25 to another.

It is also an object of the invention to provide a switch having a movable or rotating arm, and a flexible cable forming part thereof and extending therefrom, unbroken, for a 30 considerable distance.

Another object of the invention is to provide a switch having a pair of separated contacts and a switch arm movable from one of said contacts to the other, there being a 35 baffle plate interposed between said contacts to prevent the passing of an arc from one to the other, as the switch arm is moved from one of said contacts to the other.

Another object of the invention is to provide 40 a multiple switch construction wherein two separately operated switches are provided, one of which is adapted to electrically connect outside power lines to the customer's incoming lines, and the other of which 45 is adapted to connect the latter mentioned lines to the load.

A still further object is to provide a multiple 50 switch construction having two separately operated switches, with an interlock to prevent movement of one of the switches

at all times except when the other of the switches occupies certain desired positions.

Other objects will readily occur to those skilled in the art upon reference to the following description and the accompanying 55 drawings in which

Fig. 1 is a side view in elevation of the switch construction.

Fig. 2 is a front view in elevation of the 60 same.

Fig. 3 is an elevation view of a switch operating means in conjunction with the interlocking means operated thereby.

Fig. 4 is an exploded view, in perspective, 65 of details of the interlocking means.

Fig. 5 is a plan view in section of the baffle plate and shutter arrangement, and

Fig. 6 is a view in section of one of the 70 movable switch arms.

Fig. 7 is a view in section of the gang 75 shaft, taken along the line 7—7 of Fig. 2.

Referring more specifically to the drawings (Fig. 1 and 2) power lines 10 and 11 are shown entering the sectional or cellular casing 12 where they are electrically connected to the multiple contacts 13 and 14 on the disconnecting switch 15. The latter in turn is connected by means of cables 16 to the master switch 17 which may be either a non-automatic oil switch or an automatic oil circuit breaker. Pivoted handles 18 and 19 are provided for the operation of these switches, and an interlocking arrangement to prevent movement of one handle unless the other handle occupies a predetermined position, 85 is provided.

The preferred form of interlock, shown best in Figs. 2 and 4, includes a bar link 20 depending from and operated by the disconnecting switch handle 18, and provided with 90 three or more apertures 21, the number of such apertures corresponding to the number of desired positions of the disconnecting switch arm 22. In the embodiment shown, there are three such apertures 21, the switch 95 arm 22 having three desired positions, as shown in Fig. 2. Link 20 reciprocates vertically in the two part bracket 23 in such a manner that one of the apertures 21 may align with apertures 24 therein, to provide 100

a guide-way for the end 25 of the interlocking rod which, as shown in Fig. 2, is connected to the master switch handle 19 thru linkage 27 to control the movement thereof.

5 When the handle 18 has been moved so as to place disconnecting switch arm 22 in one of its desired positions, one of the apertures 21 will automatically be aligned with apertures 24, enabling rod 26 to reciprocate freely in the guideway thus formed, in turn permitting movement of linkage 27 and master switch handle 19. Reversely, when the disconnecting switch handle has not been moved and switch arm 22 is out of one of its desired positions, there will be no aperture 21 aligned with apertures 24. The latter will instead be locked by link 20, the end 25 of rod 26 abutting thereon, and movement of the switch handle 19 from its upper or open 20 switch position to its lower or closed switch position will be prevented.

Furthermore, the disconnecting switch 15 may be locked in a corresponding manner, so that it can not be opened or closed under 25 load, that is to say, when master switch 17 is closed and interlocking rod 26 is disposed within the apertures 21 and 24.

In order to preclude the possibility of a short circuit occurring between parts of the 30 disconnecting switch, and to prevent arcing between contacts as the switch arm is moved, the entire disconnecting switch assembly, with the exception of its operating handle 18, linkage 32, and gang shaft 44, is enclosed 35 or housed in a sectional or cellular casing 12, provided with cell-forming insulating partitions 33 and baffle plate 34.

The latter is slotted, as at 35, to permit main switch arms 22 to pass therethru, the 40 slots corresponding roughly in shape and in size to the arms 22. Each slot is provided with spring operated, automatically movable shutters 36 and 37, shown best in Fig. 5, to close said slots after the passage therethru 45 of arms 22, one of the shutters being opened and held open by an arm 22, the other shutter immediately closing behind that arm which traversed the corresponding slot in the baffle plate.

50 It will thus be seen that the shutters, while not interfering with the movement of switch arm 22, will, at the same time, effectually close the slots or openings in the baffle plate to assist the baffle plate in the prevention of 55 short circuits between any of the switch parts.

The disconnecting switch arm 22, movable between contacts 13 and 14 includes a switch blade 41 directly connected, mechanically and electrically, to the flexible cable 16, which 60 in turn leads to the master switch 17. Cable 16, for at least a portion of its length is surrounded by the rigid insulating sleeve 43, the latter also enclosing the connection between blade 41 and cable 16. Sleeve 43 which 65 is keyed to the bosses in shaft 44, as seen in

Fig. 7, serves also to insulatingly support cable 16 and blade 41 on gang shaft 44, the latter being mechanically connected to linkage 32 whereby movement of the handle 18 causes rotation of shaft 44 and arms 22, fixedly mounted thereon. 70

Gang shaft 44 is mounted below frame 45 of casing 12 on bearings 46 to rotate on its own longitudinal axis, and may have one or more arms 22 fixedly mounted thereon. It 75 will be noted that flexible cable 16 extends transversely thru shaft 44 and is unbroken, mechanically or electrically, from where it leaves the switch blade until it has passed thru the casing 12 and shaft 44, and a considerable distance beyond. 80

It will also be noted that the shaft and its associated parts are completely grounded thru the bearings 46 and the entire switch frame, preventing disastrous effects in case 85 of breakdown of any of the insulated parts.

This construction, eliminating as it does, the use of brushes, sliding or rotating contacts, and the like, precludes the possibility of 90 short circuits or circuit interruptions arising within or adjacent the casing 12 and the shaft 44.

95 It is also noted that the axis of rotation of the shaft 44 is between contacts 13 and 14, and at an equal distance from each of them, so that blade 41 will enter and leave the contacts on opposite sides of the shaft with equal rapidity.

100 It will also be noted that the blades 41 will travel rapidly and positively with respect to the handle 18, a slight movement of shaft 44 causing a magnified movement of blades 41.

The entire construction is such that the 105 connection between the blade 41 and cable 16 is short and direct, there being no intervening connecting members, and the whole switch with the exception of exposed blade 41 and contacts 13 and 14 are completely insulated and shielded, there being a complete insulating casing around cable 16 for at least 110 as much of its length as is contained within casing 12.

Furthermore, in case of failure or breakdown in the insulation of any switch arm, the 115 current will not pass from one arm to any other, but will go directly to ground, thru the shaft 44 and the frame of the switch, the frame, in installations of this character, being normally grounded.

Now, having described the invention and 120 the preferred form of embodiment thereof, it is to be understood that the said invention is to be limited, not to the specific details of description, but only by the scope of the claims which follow. 125

Claims:

1. In a switch, a plurality of pairs of contacts, a rotatable shaft between said contacts, the axis of rotation of said shaft being between said contacts, and a switch arm fixedly 130

mounted on said shaft, and adapted to rotate with said shaft to selectively engage said contacts, said shaft having hollow cylindrical bosses projecting therefrom, each of said bosses containing an insulating sleeve, and a cable in each of said sleeves forming part of the switch arm the end of each cable having a switch blade thereon, the sleeve enclosing the connection between the blade and the cable end.

2. In a switch, a movable shaft, a sleeve extending transversely through said shaft, a flexible cable extending thru said sleeve, and a switch blade on the end of said cable and projecting beyond the end of said sleeve.

3. In a switch, a casing, a shaft below said casing, the axis of the shaft being substantially parallel to the plane of the adjacent wall of the casing, a switch arm fixedly mounted on the shaft and projecting into said casing, the shaft being rotatable to cause movement of said arm in said casing, and having hollow cylindrical bosses projecting therefrom, each of said bosses containing an insulating sleeve, and a cable in each of said sleeves forming part of the switch arm.

4. In a switch, the combination of two contacts, a switch arm movable into and out of engagement with said contacts, and a casing for said arm and contacts, said casing being provided with a baffle plate disposed across the path of movement of said arm to shield said arm and one contact from the contact not in engagement with said arm.

5. In an electric switch, a movable shaft having a plurality of transverse bores, insulating sleeves in said bores and extending transversely thru said shaft and spaced from each other, a flexible cable in each of said sleeves, and a switch blade on each of said cables.

6. In a switch, the combination of a contact, a switch arm movable into and out of engagement with said contact, and a casing for said arm and contact, said casing being provided with a baffle plate disposed across the path of movement of said arm to shield said arm from said contact when they are not in engagement with each other.

7. In a switch, the combination of a contact, a switch arm movable into and out of engagement with said contact, and a casing for said arm and contact, said casing being provided with a baffle plate disposed across the path of movement of said arm, said baffle plate being slotted to permit movement of said arm, the slot corresponding roughly, in size and shape to that portion of the arm which passes thru it, the baffle plate serving to shield said arm from said contact when they are not in engagement with each other.

8. In a switch, the combination of a contact, a switch arm movable into and out of engagement with said contact, and a casing for said arm and contact, said casing being

provided with a baffle plate disposed across the path of movement of said arm, said baffle plate being slotted to permit movement of said arm, the slot corresponding roughly, in size and shape, to that portion of the arm which passes through it, said plate being provided with means normally closing said slot, said baffle plate and said means serving to shield said arm from said contact when they are not in engagement with each other.

9. In an electric switch, a casing, an insulating sleeve in said casing, an electric cable in said sleeve, and a switch blade electrically and mechanically connected to said cable, the insulating sleeve completely enclosing the connection between said blade and said cable and also enclosing the entire length of said cable contained within said casing.
